ATTORNEY

UNITED STATES PATENT OFFICE

LEONARD S. COPELIN, OF LOS ANGELES, CALIFORNIA

ROTARY CORE DRILL

Application filed September 4, 1928. Serial No. 303,757.

My invention relates to the art of taking cores by what is commonly known as the rotary method of drilling.

Difficulty is at times experienced in obtaining cores truly typical of the formation in which operations are being carried on, such difficulty being in part due to the fact that in penetrating hard formations the core becomes highly heated and swells thereby adhering to the walls of the core receiving opening in the drill. When cores stick in the drill as above referred to, the continued rotation of the drill breaks the core and further recovery of core is stopped until the clogged condition of the core receiving opening has been remedied, which in many cases is not accomplished until the drill has been raised from the hole.

It is the principal object of my invention to produce a device of simple form and construction which is insertable in the core receiving opening of the drill close to the mouth of such opening which will relieve the binding action of the core in such opening.

This device consists of a ring having laterally extending openings therethrough which ring is freely and rotatably mounted in the core receiving opening of the drill close to the mouth of such opening.

Other objects and advantages will appear hereinafter from the following description and drawings.

Referring to the drawings which are for illustrative purposes only

Fig. 1 is a side elevation partly in section showing a core drill embodying a form of my invention.

Fig. 2 is an enlarged vertical sectional view of the lower end of the drill shown in Fig. 1.

Fig. 3 is an enlarged sectional plan view on line 3—3 in Fig. 2.

Fig. 4 is an enlarged perspective view of the form of ring used in one embodiment of my invention.

Fig. 5 is a perspective view similar to Fig. 4 showing a modified form of ring and

Fig. 6 is a vertical elevation of the lower end of the drill shown in Fig. 1.

More particularly describing my invention as shown in the drawings, 11 designates a

body member, 12 the outer barrel and 13 the inner barrel, the upper end of the outer barrel being provided with a sub 14 for connection with the ordinary drill pipe, not shown.

The upper end of the inner barrel or core barrel 13 is provided with a valve 16 by means of which circulating fluid entrapped in the core barrel may be discharged from above the advancing core.

Secured to the lower end of the inner barrel as by welding indicated at 18, is a collar 19 interiorly threaded to receive the upper end of a sleeve 20, the lower end of such collar being seated on a shoulder 21 formed in the body member 11.

The lower end of the body member 11 is provided with a transversely extending slot 22 which receives keys 23 formed on the upper end of a cutting head 24, such connection of the cutting head to the body member being fully shown and described in my former Patent Number 1,599,810. The lower end of the sleeve 20 is seated on a shoulder 26 formed in the cutting head, the lower end of the sleeve being exteriorly threaded to receive the interiorly threaded portion of the cutting head 24 as shown in Fig. 2.

The lower end of the cutting head 24 terminates in a circular toothed cutter 27 formed about a central core receiving opening 28. Just above the teeth in the cutter 27 is an annular recess 30 in which is freely rotatably mounted a ring 31 having a series of perforations or openings 32 extending therethrough.

This ring is retained in the recess 30 by the lower end of the sleeve 20 which is provided with a core receiving opening 33 of approximately the same diameter as the core receiving opening 28 in the cutting head, the internal diameter of the ring 31 being slightly larger than such openings. The ring shown in Figs. 1 to 4 inclusive is a solid ring and is placed in the annular recess 30 prior to completion of the assembling of the parts of the drill, but if desired a split ring 36 as shown in Fig. 5 may be used and inserted in the annular recess after the parts are assembled.

The cutting head 24 is provided with two sets of cutting blades, the lower set consisting of lower blades 40 angularly disposed on the

head 24 and extending outwardly therefrom and an upper set consisting of blades 41 which extend outwardly a greater distance than the blades 40 such blades 41 preferably having straight forward faces 42. By angularly disposing the blades 40, I find that the drill has greater drilling speed and that the straight blades 41 tend to steady the drill in the hole.

10. In operation the circulating fluid is pumped through the drill between the outer and inner barrels, being discharged through outlets 45. As the drill cuts away the formation the core enters the opening 28, such core being under ordinary conditions of slightly smaller diameter than the opening 28 and coated with mud or circulating fluid which works upwardly with the core with the recess 30, some of the fluid or mud filling the openings 32 in the ring 31 thereby affording an additional supply of core lubricating material, the core being retained in the core barrel by means of a core catcher consisting of a tube 50 seated on a shoulder 51 in the sleeve 20 and being provided with spring fingers 52.

15. In cases however where hard formation is encountered the cutter becomes hot due to the slow progress of the drill through such formation. This results in heating and expanding the core which in the ordinary core drill sticks in the core receiving opening, such drills having a long uninterrupted opening below the core catcher. This results in the core plugging the core receiving opening, the core rotating with the drill with consequent grinding up of the formation and failure to take core with the further result that such core as is recovered is contaminated with the cuttings and fails to show a representative sample of the formation being drilled.

20. In my invention the ring 31 forms part of the core receiving opening and is free to remain stationary with respect to the drill as the drill rotates, the friction, if any, being between the ring and drill instead of between the core and drill. The circulating fluid or mud in the recess 30 under such conditions works around the core and provides an additional lubricant supply so that the core does not become overheated and stick in the drill.

25. In my invention the rotation and twisting action on the core is greatly reduced so that the core enters the barrel and a true sample is recovered.

30. I claim as my invention:

1. In a rotary core drill having a core catcher, a cutting head having a core receiving opening formed with an annular recess therein below said core catcher, and a freely rotatable ring in said recess.

35. 2. In a rotary core drill having a core catcher, a cutting head having a core receiving opening formed with an annular recess therein below said core catcher, and a freely rotatable ring in said recess, said ring hav-

ing a plurality of lateral openings extending therethrough.

3. In a rotary core drill having a core catcher, a cutting head having a core receiving opening, a circular cutter consisting of a series of teeth formed about said opening, said cutting head having an annular recess formed in said opening close above said circular cutter and below said core catcher, and a freely rotatable ring in said recess having a plurality of lateral openings extending therethrough. 70

4. In a rotary core drill having a core catcher, a cutting head having a core receiving opening formed with an annular recess therein below said core catcher, and a freely rotatable split ring in said recess. 75

5. In a rotary core drill, a body member, a sleeve in said body member, a cutting head threaded to said sleeve having a core receiving opening, said cutting head having an annular recess formed in said opening, and a freely rotatable ring in said recess retained therein by the lower end of said sleeve. 80

6. In a rotary core drill, a body member, a sleeve in said body member, a cutting head threaded to said sleeve, having a core receiving opening, said cutting head having an annular recess formed in said opening, and a freely rotatable ring in said recess retained therein by the lower end of said sleeve, and a core catcher in said sleeve above said ring. 85

7. In a rotary core drill, a cutting head having a core receiving opening formed with an annular recess therein, and a freely rotatable ring in said recess, said ring being of slightly larger internal diameter than the core receiving opening in said cutting head. 90

8. In a rotary core drill, a cutting head having a core receiving opening formed with an annular recess therein, and a freely rotatable ring in said recess, said ring being of slightly larger internal diameter than the core receiving opening in said cutting head, and having a plurality of lateral openings extending therethrough. 95

9. In a rotary core drill having a core catcher, a cutting head having a core receiving opening therein and an anti-friction ring in said opening below said core catcher. 100

In testimony whereof, I have hereunto set my hand at Los Angeles, California, this 23 day of August, 1928.

LEONARD S. COPELIN.
